TUBE BENDING

Homer J. Steel, 925 Madera Circle, P.O. Box 392,
Elm Grove, Wis.
Continuation of application Ser. No. 157,520, Dec. 6,
1961. This application Apr. 26, 1965, Ser. No. 463,415
41 Claims. (Cl. 29—157)

This application is a continuation of my copending application, Serial No. 157,520, filed December 6, 1961 and now abandoned.

This invention relates to improvements in machines for forming of short lengths of pipes or tubing into elbows or bends for connection by welding or otherwise into piping systems.

In the forming of pipe fittings such as elbows from short lengths of standard seamless pipe blanks, it is desirable to secure uniform curvature in the bend as well as to maintain roundness of cross section of the pipe. It is desirable to reduce to a minimum changes in pipe wall thickness, that is thinning along the major or outer bend radius wall and thickening of the minor or inner bend radius wall. Scoring or otherwise deforming either the interior or exterior surfaces of the above should be avoided, as well as any effects which would lead to weakness of the fitting or disturbances in the flow of fluids through the fitting. An A.S.T.M. specification states the tolerances allowable for such fittings and the present invention has proven capable of meeting both the above general requirements and the A.S.T.M. specification for welding fittings.

Generally in accordance with one aspect of the present invention, the elbows are formed by pressing the pipe lengthwise through a passage formed between dies having grooves therein. In one embodiment shown, a free traveling mandrel has its leading end disposed within the trailing end of a preceding workpiece for supporting and holding the latter. The trailing portion of said free mandrel is disposed within and supports the leading end of a following workpiece. In accordance with another aspect of the invention, and in another embodiment, a workpiece is pressed into and against the trailing end of a traveling mandrel which is supported and held for arcuate movement about a grooved roller die and which acts against a yielding resistance. In each case the trailing end portion of the mandrel bears radially inwardly toward the inner support as a fulcrum and presses radially inwardly within the pipe. The trailing end portion of the mandrel within the pipe progressively bears against the outer pipe wall from the forward end thereof toward the pipe center while the pipe is held along its inner surface against the support.

In all instances, the workpiece blank is moved progressively along a curved inner groove from an initial position substantially tangential to the groove and in contact with the die until the elbow is formed.

The structure may include a plunger associated with a supporting roller and which coat in one embodiment with fixed forming members and a fixed guide block to define a passage of the cross sectional size and radius desired, and coacting in another embodiment with means yieldingly holding the pipe on the roller with such means slowly giving way under resistance of a hydraulic or air cylinder. The rotatable forming roller and the fixed forming members are all made of high grade steel and provide a very rigid structure when assembled in a suitable frame. In each case, two traveling mandrels act in shaping the walls of a pipe to conform to the curvature of the forming passage. In each case, one mandrel is fixed to a plunger for applying pressure to the end face of the pipe. In one embodiment, the other mandrel is

2

free from any machine parts and travels with workpieces moving through the forming passage, while the second embodiment has the other mandrel connected with a resisting hydraulic cylinder. The free traveling mandrel has a collar extending outward about the middle of the mandrel for engaging the end faces of the pipe.

The spaced mandrels are made of high grade steel and have an outer surface dimension conforming to the inner dimension of the outer wall of the finished workpiece, and are curved in three dimensions from the mid-region toward the end to provide compound curved surfaces which roll at different times on the outer radius of an elbow. In the first embodiment, the free mandrel is elongated and has compound curved surfaces toward both its leading and trailing end, forming a generally banana-shaped object. The point of the leading end of the mandrel is relieved to facilitate entrance into the preceding workpiece. The outer surfaces of the mandrels are arcuate in both the longitudinal and transverse directions and the inner surfaces are generally straight longitudinally but curved transversely, that is cylindrical, so that the mandrel comes nearly to points at the ends and provides compound curved lower surface portions.

In the drawings:

FIGURE 1 is a vertical cross sectional view of one embodiment of my present machine for cold forming pipe fittings, with the plunger of a press shown bearing on one workpiece and a free mandrel disposed between that and a preceding workpiece;

FIG. 2 is a perspective view of the sleeve which is attachable to the press plunger for exerting force on the workpiece;

FIG. 3 is a fragment of FIGURE 1 showing the interaction of one workpiece and the forming surfaces acting thereon at the end of a pressure plunger stroke;

FIG. 4 is a diagram showing the position and shape of two workpieces in the machine at a time intermediate loading and discharge of the devices;

FIG. 5 is an elevation of a blank showing the initial shape of the ends thereof;

FIG. 6 is an elevation of a bent workpiece formed from the blank of FIG. 5;

FIG. 7 is an elevation showing the workpiece of FIG. 6, trimmed to length and beveled to form an elbow for welding in place between two lengths of piping;

FIG. 8 is a side elevation of one-half of a stationary die structure which may be substituted for the other die members in the machine of FIGS. 1-4;

FIG. 9 is a front elevation of the complete die of FIG. 8;

FIG. 10 is a plan view of the forming roller and showing the die groove, and the elongated bearing portions of the roller;

FIG. 11 is a view partially in section and partially in elevation of a second embodiment of the present machine showing a mandrel having an end which provides a yieldable counter-force acting on the workpiece;

FIG. 12 is a fragmental view similar to FIG. 11, but showing the machine parts and a workpiece in a position when the workpiece is partially formed; and

FIG. 13 is a fragmental view similar to FIG. 11, but showing the machine parts and a workpiece in position when the workpiece has been fully formed.

As shown in FIGURE 1 of the drawings, a horizontal base 15 of heavy metal plate has fixed thereto a heavy metal vertical frame 16 which is substantially U-shaped in plan and which has an aperture through the frame. Rotatable forming means, such as a roller 17 is disposed with the ends thereof supported on a number of roller bearings 18 in the frame 16, only one bearing being shown. The portion of roller 17 inside the space de-

ned by the frame, is shaped to provide a die groove of the size and of inner radius corresponding to the inner curved surface of the fittings to be formed thereby. In dimensioning the groove in roller 17, the radius of the groove should conform to the inner surface radius desired for a workpiece of a particular size. A generally L-shaped and grooved die member or support 22 is seated in fixed position in frame 16 between a vertical backplate 23 and a bottom plate 24. Thus support 22 can be easily brought into position around roller 17 so that some of the edges of the groove of support 22 conform to the edges of the groove in the roller.

A vertical guide block 25 is formed with a die groove complementing the groove in fixed support 22 and has its edges mating with some of the edges of support 22 so that a passage of desired size is provided. The lower edge of guide block 25 conforms to the surface of roller 17 and the groove therein coacts with the groove in support 22 to define the entrance to the forming passage through which the workpieces are pressed. The guide block 25 is held in place by a screw 29 threaded into a cross piece 30 removably seated in notches in the legs of frame 16 and extending across the space therein.

A horizontal former plate 31 forms an extension of the lower portion of support 22 and is held in place against the support by a screw 32 threaded into cross piece 33 which is also held in notches in frame 16 and extends across the recess in such frame. Former plate 31 is to provide a continuation of the groove in support 22. The groove in support 22 and continuing into former plate 31 is shaped to a diameter to produce the desired outer radii of the pipe bend.

As shown in FIG. 5, the hollow pipe blanks to be shaped into elbows and bends are cut into short pieces 34 so that the outer radius of the finished piece is formed from portion 35, and the inner radius thereof is formed from portion 36. Thus, additional metal is provided where the workpiece wall tends to lengthen. The leading end of the workpiece which enters the forming passage is irregular and cut at a right angle to the workpiece's longitudinal centerline, as at flat portion 37, while the adjacent end portion 38 is cut at an acute angle to the said centerline. The trailing end of the workpiece is also irregular and cut at a right angle to the longitudinal centerline as at flat portion 39, and is cut at an acute angle to the longitudinal line as at 40. This second angle is much smaller than the first angle. After final forming, and as shown in FIG. 7, the elbows are cut to the length specified and the ends are beveled as at 41 for welding to similarly beveled ends of piping.

For purposes of pipe forming, an elongated solid, rigid traveling mandrel 46 is provided which is completely free from any machine parts. Mandrel 46 has an annular seat or rim-like collar 47 formed midway of the length thereof. As shown in FIGS. 1, 3 and 4, the inner surface portion 48 of mandrel 46 is straight longitudinally but curved transversely while the outer surface thereof is curved both longitudinally and transversely to provide continuous compound curved trailing outer surface 49 and leading outer surface 50. The mandrel is thus generally banana-shaped with generally pointed ends. The inner leading end portion of the mandrel is shaped as shown at 51 to facilitate entrance into the preceding workpiece.

As shown in FIGS. 1-4, free mandrel 46 is adapted to cooperate with and assist in forming two workpieces in succession. During forming, the leading end of the mandrel is adapted to enter and be enclosed within the trailing end of a preceding workpiece, while the trailing end of the mandrel is adapted to enter and be disposed within the leading end of a following workpiece, and acting as a cantilever in support of the wall.

The inner surface 48 of the mandrel conforms to the bore of the workpiece and the outer surfaces 49, 50 of

the mandrel conform severally to the outer wall of the workpiece as the mandrel moves about the roller.

The workpieces are pressed in succession in a curved path, that shown being circular, by a sub-assembly including a plunger 55 formed at its pressing or leading end 56 in the banana-like shape of the leading portion of mandrel 46. Plunger end 56 is fixedly mounted in a sleeve 57 which is shown in FIGS. 2 and 3 in enlarged scale. The leading outer portion of the sleeve end is irregular and cut back, to form a step 58, and is transverse to the sleeve centerline to thus make two sharp corners with intermediate forwardly extending tooth portions 59 of the sleeve, while the inner portion of the sleeve end forms a slightly cut back angular portion 60.

Prior to the first complete forming operation, a scrap workpiece is inserted into the forming passage and plunger 55 is moved downwardly. The scrap workpiece is thus forced downwardly and partially through the passage. Plunger 55 is then withdrawn and a free mandrel 46 is inserted into the passage so that the leading mandrel end is disposed within the trailing end of the scrap workpiece and mandrel collar 47 bears on the workpiece's trailing end. This scrap workpiece assumes the position that all later-formed workpieces do, the numeral 34a in FIGURE 1 of the drawings designating either the scrap workpiece or a subsequent workpiece in the same position.

A second workpiece 34b is now inserted with its forward end over the trailing end of mandrel 46, and the press plunger 55 is again brought to bear on the trailing end of workpiece 34b and fixedly moves therewith.

Plunger 55 again moves downwardly and the step 58 thereof contacts the flat trailing end portion 39 of workpiece 34b. As workpiece 34b begins to move around the bend, the metal flows so that the toothed portion 59 of the sleeve end digs into the workpiece end and progressively seats on some of the surface 40 of the workpiece. The inner portion of surface 40 is free to expand longitudinally and toward sleeve 57. (See FIG. 3.) Mandrel 56 and workpiece 34b move together at all times, no substantial relative axial movement occurring therebetween.

As the bend in the forming passage is reached, the trailing end of mandrel 46 will rock so that its trailing outer surface 49 progressively contacts and supports the outer wall of workpiece 34b and presses it into the forming groove. (Compare FIGS. 1 and 3.) This will support the outer wall fibers of the leading half of workpiece 34b against flattening in a rearwardly progressing manner from the forward end thereof toward the workpiece midportion. At the same time, inner surface 48 of mandrel 46 will support the inner wall fibers from collapse at the leading end of workpiece 34b in line contact continuously during formation of the bend.

The free mandrel and the outer wall of workpiece 34b remain fixed relative to each other during the bending operation, with substantially no relative axial movement occurring. Both move only arcuately.

The outer wall of the second workpiece 34b will tend to stretch in tension during the bending operation. (See FIG. 4.) However, rim 47 of the mandrel will put lengthwise compression on the outer wall of the leading end of the workpiece, as at flattened portion 37, which adds to the lengthwise compressive forces generated by sliding friction between the outer surface and support 22. As best seen in FIG. 4, the inner wall of the second workpiece 34b will be unconfined longitudinally and may shorten slightly. The major amount of plastic flow will be along the neutral axis extending generally intermediate the inner and outer surfaces with the plane of the ends being readjusted. Both ends of the workpiece will end up generally planar, as shown in FIG. 6.

Throughout bending, the forward end of mandrel 46 will rigidly anchor within the trailing end of the inner wall of first workpiece 34a and causes the mandrel as a whole to act as a cantilever in applying outward oriented forces by the trailing end of the mandrel. In addition,

the forward end of the mandrel will support the trailing end of the outer wall of workpiece 34a after the aforementioned rocking action has taken place.

When plunger 55 reaches its lowermost position, as in FIG. 3, the preceding workpiece 34a (which is scrap in the preliminary operation but a finished piece in subsequent operations) is removed. The plunger is again retracted, a mandrel 46 is placed in the remaining workpiece's trailing end, a new workpiece is placed over the mandrel, and the entire process is repeated as often as desired.

Stainless steel tubing has a tendency to gall when subjected to cold bending and sliding in close frictional contact with another surface. Instead of using an inner forming roller and fixed outer grooved members, a die made wholly of stationary parts of a suitable alloy may then be used as shown in FIGS. 8 and 9. FIG. 8 shows one-half of a stationary former member made of an alloy having high strength and non-galling properties, aluminum bronze having been found satisfactory. The completed former includes the right hand half 64 and a left hand half 65 exactly located relative to each other as by dowels 66 and the two halves are held against spreading by bolts 67. The present modification may be held on a suitable press. The use of a free traveling mandrel 46 and the sequence of steps is as described for FIGS. 1-4.

Referring now to FIGS. 11-13, a die member such as a roller is again employed but the free traveling mandrel is now replaced by a forward mandrel fixedly connected to the roller. Loading of the device is simplified, there is increased accuracy of positioning of the pipe length and improved action of the forward mandrel on the workpiece. The forming machine is again made with a relatively heavy horizontal base 70 and a frame of spaced vertical pedestals 71 extending above and fixed to the base. A 35 grooved forming roller 72 is mounted to extend across the space between the pedestals and is rotatable in a number of suitable bearings 73. The roller 72 is now fixedly attached to a leading mandrel sub-assembly, including a block 74, which in turn has attached to it a lever arm 75 connected with the piston 76 of a pressure power cylinder 77 which is pivoted at 78 on a reaction member 79. This creates a resisting torque on the roller. The pressure cylinder and piston are constructed to provide a moderate resistance to roller movement and can be controlled to position the roller. The block 74 has a socket and hole in which is mounted a portion of a rigidly mounted forward mandrel 83 held captive in the block by way of a bolt 84. Mandrel 83 corresponds in shape and function to the trailing half of mandrel 46. The mandrel 50 83 has an annular collar 85 at its forward end for seating thereon of a sleeve 86. The forward end of sleeve 86 is planar, while the rearward end is tapered so that the taper of the forward end of a pipe 34 inserted over mandrel 83 will be generally complementary thereto. A shallow cup is left in the socket of block 74 to receive the 55 end of workpiece 34 and affords a radial support to the outer fibers at the leading end of the workpiece.

A grooved die or guide 89 slideable on base 70 supports a pressing mandrel sub-assembly, including a pressure plunger 90, with the latter having a banana-like 60 plunger mandrel portion 91 fixed thereto and a sleeve portion 92 having its end formed in a manner similar to that of FIGS. 1-4. The plunger 90 is rigidly secured to guide 89 by a suitable clamp 93. The mandrels 83 and 65 91 are captive to their respective mountings and the leading end of the mandrel 91 is cut short to clear the end of the mandrel 83 as shown in FIG. 11.

In operation, when block 74 and its captive mandrel 83 are in the position shown in FIG. 11 and plunger 90 and 70 mandrel 91 are retracted, a workpiece 34 may be loaded to seat on the sleeve 86 and rests in grooved die 89. The press plunger sleeve 92 is then moved endwise in a straight path to engage and move the workpiece against the yielding pressure of the fluid pressure cylinder 77. The force 75

of press plunger 90 must be strong enough to overcome the resistance in cylinder 77. Block 74 and its mandrel 83 will then successively move arcuately and in a curved path about the center of the roller groove to the positions shown in FIGS. 12 and 13. In FIG. 12, the workpiece is being formed arcuately around the forming roller 72 by the forward captive mandrel 83 and by the shallow cup surrounding it. As in the first embodiment, mandrel 83 will rock so that its trailing outer surface progressively contacts and supports the outer wall of the leading half of the workpiece against flattening. (Compare FIGS. 11 and 12.) At the same time, the inner surface of mandrel 83 will support the leading inner end of the workpiece in line contact against collapse at all times during formation of the bend, as well as helping the shallow cup to force the workpiece inner wall into the roller groove. Plunger mandrel 91 will support the trailing inner end in area contact against collapse at all times and allow the inner fibers to adjust themselves longitudinally by shearing action, as shown in FIG. 13. In addition, there is no substantial axial or longitudinal movement between the mandrels and the workpiece during bending. The grooved die 89 provides inwardly directed bending pressure in coaction with mandrel 91 on the trailing end of the workpiece and sizes the O.D. In the position shown in FIG. 13, the bend is completed. The pressure is then reversed in cylinder 77 while plunger mandrel 91 is retracted to its initial position. The bent workpiece is then manually removed, after which the cylinder 77 is actuated to return forward mandrel 83 and roller 72 to their initial position, thus completing the cycle.

In this second embodiment, there is no outer groove comparable in purpose to the groove in support 22 and former plate 31 of FIGURE 1, except for the groove in guide 89.

The present invention provides for substantially improved tube bending procedures when cold forming is desired. Collapse of the walls is prevented during the forming operation, as contrasted with prior procedures wherein collapse occurs and the workpiece must then be restored. The walls of the finished workpiece are substantially uniform throughout.

Various modes of carrying out the invention are contemplated as being within the scope of the following claims particularly pointing out and distinctly claiming the subject matter which is regarded as the invention.

I claim:

1. In a machine for cold forming a length of pipe into a bend:
  - (a) a frame,
  - (b) a roller with a peripheral groove having a partial cylindrical cross section and rotatably mounted in the frame,
  - (c) a member on the frame for coacting with the roller in providing a passage for forming a pipe into a bend of given inner and outer radii,
  - (d) first means for receiving the leading end of a pipe within the forming passage and disposed to travel with the pipe through the forming passage in fixed axial relation to the pipe, said first means being constructed to progressively support the outer wall of the pipe against flattening in the leading half portion thereof during said travel,
  - (e) and second means for entering the trailing end of the pipe and disposed to travel in fixed axial relation therewith through a portion of the passage,
  - (f) said first and second means coacting in forming the pipe into the passage radii.
2. The machine of claim 1 in which the second means comprises a pressure plunger having a sleeve fixed thereon for bearing on the trailing end of the pipe in fixed relation to the end of the plunger and in which the sleeve bears on only a portion of the pipe trailing end by way of a step and teeth between the pipe outer and inner ra-

7
lius walls and is spaced from the pipe end at the inner radius wall thereof.

3. The machine of claim 1 in which the first means comprises a leading mandrel having a collar extending outwardly therefrom midway of the mandrel length for simultaneous bearing thereon of an end of two successive pipe lengths.

4. The machine of claim 1 in which the first means comprises a leading mandrel having a collar extending outwardly therefrom midway of the mandrel length for bearing thereon of successive pipe lengths and being of a diameter substantially equal to the diameter of the forming passage for coaxing with the leading pipe length in yieldingly resisting axial movement of the following pipe during movement through a portion of the passage.

5. The machine of claim 1 in which the first means comprises a leading mandrel having an external collar midway of its length and the mandrel tapers from the collar toward both mandrel ends for supporting both the inner and outer radius pipe walls in the leading half portion of the pipe, and the second means comprises a pressure plunger having a forward end similar in shape to the adjacent end of the leading mandrel.

6. In an apparatus for forming elbows from straight tubular blanks,

- (a) a die member having a groove therein with a portion curved corresponding to the minimum inner radius of the elbow to be formed,
- (b) means to move the blank progressively along said curved groove from an initial position substantially tangential to said curved portion and in contact with said die member until the elbow is formed,
- (c) and spaced blank forming means disposed inside the blank at each end thereof and having an outer dimension and configuration corresponding to the inner dimensions of the finished elbow in the portion of maximum radius, the blank forming means disposed at the leading end of the blank being constructed to act as a cantilever to progressively support the outer wall of the pipe against flattening in the leading half portion thereof during movement of the blank,
- (d) said forming means fixedly moving with the blank during the elbow forming operation.

7. The apparatus of claim 6 which includes: yieldable means for resisting the movement of said blank during travel thereof in said groove.

8. The machine of claim 6 in which said die member comprises a movable forming roller, and a piston under pressure is connected with the roller for yieldingly resisting movement thereof.

9. The machine of claim 8 in which the said blank forming means comprises a leading mandrel and a trailing pressure plunger, said mandrel and said plunger having a sleeve fixed thereon and bearing on the respective pipe ends in fixed axial relation to the pipe during movement of the pipe around the roller.

10. In an apparatus for continuously forming elbows from straight tubular blanks,

- (a) die means forming a curved passageway for receiving a series of blanks in succession therethrough,
- (b) and means to move the said blanks progressively in succession through said passageway, said moving means including a free mandrel disposed within said passageway,
- (c) the forward end portion of said mandrel being formed to be disposed within the trailing end portion of a preceding blank for supporting said trailing end portion against collapse,
- (d) the rearward end portion of said mandrel being formed to be disposed within the forward end portion of the next succeeding blank for supporting the latter end portion against collapse,
- (e) said mandrel fixedly moving in said passageway with both said preceding blank and said next suc-

ceeding blank during the elbow forming operation.

11. The apparatus of claim 10 in which the mandrel comprises:

- (a) an elongated generally banana-shaped member,
- (b) the inner surface portion of said mandrel being generally straight longitudinally but curved transversely,
- (c) the outer surface portion of said mandrel being curved both longitudinally and transversely to provide continuous compound leading and trailing outer surfaces,
- (d) the said mandrel being constructed to rock in said passageway so that the trailing compound outer surface of said mandrel contacts the outer wall of the leading end portion of the said next succeeding blank progressively from the end of the blank rearwardly toward the midportion thereof to support said wall against flattening during formation of the bend.

12. The apparatus of claim 11 in which the said mandrel includes an annular rim disposed centrally thereof for seating the trailing and forward ends of two blanks traveling in succession.

13. For use in an apparatus for forming elbows from straight tubular blanks, a free mandrel comprising:

- (a) an elongated generally banana-shaped body adapted to enter and support the walls of adjacent blanks,
- (b) the inner surface portion of said body being generally straight longitudinally but curved transversely,
- (c) and the outer surface portion of said body being curved both longitudinally and transversely to provide continuous compound leading and trailing outer surfaces,
- (d) and an annular rim disposed centrally of said body for seating the trailing and forward ends of two blanks to be formed.

14. For use in an apparatus for forming elbows from straight tubular blanks, a mandrel comprising:

- (a) a body portion adapted to enter and support the forward end portion of a blank to be formed,
- (b) and stop means disposed on said body for seating the forward end of a blank,
- (c) said body portion being shaped to support the outer wall of the blank progressively from the forward end thereof and rearwardly toward the central portion thereof during formation of the elbows.

15. In an apparatus for forming elbows from straight tubular blanks:

- (a) means to move a blank in a curved path,
- (b) means to support the rearward end portion of a blank against collapse as it is moved in said path,
- (c) and rigid means adapted to be disposed within the leading end portion of a blank, said last-named means being shaped to contact and support against flattening the outer wall of said leading end portion in a progressive manner from the end of the blank rearwardly toward the central portion thereof during movement of the blank in said path.

16. The apparatus of claim 15 which includes means to support the leading end of the inner wall of a blank against collapse continuously during movement of the blank in said curved path.

17. In an apparatus for forming an elbow from a straight tubular blank having an irregular trailing end with an outer flat transverse portion and a tapered inner portion:

- (a) means for moving said blank in a curved path to form an elbow,
- (b) said means including a member for contacting the trailing end of the blank,
- (c) said member having a toothed portion which digs into the blank progressively as the metal flows during forming.

18. In an apparatus for forming elbows from straight tubular blanks:

- (a) means to move a blank in a curved path so that its outer wall tends to lengthen,
- (b) and means to confine the ends of said outer wall to substantially reduce lengthening thereof during movement of the blank in said curved path, said means comprising:
  - (1) a first member engageable with the trailing end face of said outer wall,
  - (2) and a second member disposed for longitudinal engagement with the forward end face of said outer wall,
  - (3) both said members fixedly traveling with the blank during forming.

19. The apparatus of claim 18 in which said blank and members are constructed and disposed so that the inner wall of the blank is unconfined longitudinally.

20. In an apparatus for forming elbows from straight tubular blanks:

- (a) a die forming a curved supporting surface for receiving the inner radius wall of a blank,
- (b) a plunger engageable with the outer trailing end face of a blank and with said plunger being movable in a straight path,
- (c) a first mandrel connected to said plunger and disposable within the said trailing end of the blank for supporting the latter,
- (d) a member disposable adjacent the forward end of the blank and movable arcuately about the center of said curved surface,
- (e) and a second mandrel separate from said first mandrel and connected to said member and disposable within the forward end of the blank for supporting the latter and with said second mandrel having a portion supporting the outer leading end face of the blank.

21. The apparatus of claim 20 which includes: yieldable means connected to said member for resisting arcuate movement thereof as a blank is being formed around said supporting surface by movement of said plunger.

22. The apparatus of claim 20 which includes: a die member fixed for straight movement with said plunger and having a groove for supporting the trailing end of the blank during forming.

23. In an apparatus forming elbows from straight tubular blanks:

- (a) a die forming a curved supporting surface for receiving the inner radius wall of a blank,
- (b) a plunger engageable with the trailing end of a blank and with said plunger being movable in a straight path,
- (c) a first mandrel connected to said plunger and disposable within the said trailing end of the blank for supporting the latter,
- (d) a member disposable adjacent the forward end of the blank and having a shallow cup therein and movable arcuately about the center of said curved surface,
- (e) and a second mandrel rigidly mounted within said cup and thereby spaced from said member,
- (f) said second mandrel adapted to receive the forward end of the blank thereover so that said forward end is disposed within said cup and supported by the wall of said cup, said second mandrel being shaped to progressively contact the outer wall of the blank from the forward end of the wall rearwardly toward the midportion thereof.

24. In a machine for cold forming a pipe workpiece into a pipe bend, a cylindrical rotary former having an arcuate peripheral groove therein, a pressing mandrel sub-assembly having a portion insertable into and a portion

a straight line while holding the workpiece in the rotary former groove, a leading mandrel sub-assembly having a portion insertable into and a portion pressing endwise on the workpiece and movable in an arc about the rotary former axis for holding the workpiece in the rotary former groove, both the inserted mandrel portions remaining in the moving with the workpiece during forming thereof, and power means for yieldingly resisting movement of the rotary former and the leading mandrel during forming action and returning the same to an initial position after the formed workpiece is removed.

15 25. The machine of claim 24 in which the pressing mandrel sub-assembly moves in a straight line parallel with a line tangent to the rotary former groove and the leading mandrel sub-assembly is mounted on and moves in an arc about the rotary former.

20 26. The machine of claim 24 in which the mandrel sub-assemblies severally comprise a mandrel for insertion into the workpiece and a sleeve for endwise engagement with the workpiece, the mandrels severally having a cylindrical surface portion for pressing the workpiece into the rotary former groove for forming an inner bend workpiece wall, and the leading mandrel having a compound curve portion for forming an outer bend workpiece wall while the inner wall is being formed.

25 27. The machine of claim 24 in which the mandrel sub-assemblies severally comprise a mandrel for insertion into the workpiece and a sleeve for endwise engagement with the workpiece, the sleeves being relieved at the end for endwise engagement with the workpiece only on the workpiece end portions inwardly from the outer bend wall surface, said outer bend wall portions of the workpiece being longer than the inner bend wall portions and the metal of the inner bend wall flowing into the relief space of the sleeve.

30 35 40 28. The device of claim 24 in which the power means are fluid pressure actuated and are provided with control means for turning the rotary former and leading mandrel to an initial position after retraction of the pressing mandrel to its initial position.

29. In a machine for cold forming a pipe workpiece into a pipe bend, a rotary former having an arcuate peripheral groove therein, a pressing mandrel sub-assembly having a portion insertable into and a portion pressing endwise on the workpiece and movable in a straight line while holding the workpiece in the rotary former groove, a holder for movement with and relative to the pressing mandrel and grooved to receive the workpiece, a leading mandrel sub-assembly having a portion insertable into and a portion pressing endwise on the workpiece and movable in an arc for holding the workpiece in the rotary former groove, and power means for yieldingly resisting movement of the rotary former in one direction and turning the rotary former in the other direction.

30 35 40 45 50 55 60 65 70 75 29. In a method for forming lengths of metal pipe into elbows, the steps of cutting the ends of a length of pipe to provide at the outer radius of the elbow end surfaces perpendicular to the pipe centerline and an end surface inclined at an acute angle to the pipe centerline, the cutting being such that the areas of inclined end surfaces are greater at the trailing end of the pipe than at the leading end thereof to provide for flow of a greater amount of metal toward the trailing pipe end during forming, inserting the pipe into a cylindrical passage having a curve with an inner and an outer radius dependent on the dimensions of the length of pipe, placing the leading end of the pipe over a mandrel adapted to traveling with the pipe around the curve of the passage, and pressing on the trailing perpendicular end surface of the pipe for forcing the pipe and the mandrel around the curve of the passage while supporting the outer pipe wall progressively from the forward pipe end rearwardly toward the pipe midportion.

11

31. In the method of forming straight tubular blanks into elbows, the steps comprising:
- cutting a blank so that the outer portion of each end is flat and the inner portion of each end is angularly tapered relative to the centerline of the blank, with the angle of taper on the trailing end being smaller than the angle of taper on the leading end thereof,
  - positioning a blank for movement in a curved path,
  - placing the leading end portion of said blank over a mandrel,
  - and moving said blank and said mandrel in fixed relation around said curved path by pressing initially on the flat portion of the trailing end of the blank and subsequently progressively pressing on the tapered portion of the said trailing end.
32. The method of claim 31 which includes the step of holding the said outer wall of said blank under compression simultaneously with the said moving of the blank in a curved path.
33. In a method of forming straight tubular blanks into elbows, the steps comprising:
- providing a hollow blank for movement in a curved path,
  - positioning a mandrel forwardly of the forward end portion of said hollow blank,
  - positioning the said forward end portion of said blank over said mandrel,
  - and moving said blank and said mandrel in fixed relation around said curved path by pressing on the trailing end of the blank while longitudinally confining the outer wall of the blank.
34. In a method of forming straight tubular blanks into elbows, the steps comprising:
- providing a blank for movement in a curved path,
  - positioning a mandrel forwardly of the forward end portion of said blank,
  - positioning the said forward end portion of said blank over said mandrel,
  - moving said blank and said mandrel in fixed relation around said curved path by pressing on the trailing end of the blank,
  - and continuously holding the outer wall of said blank under lengthwise compression simultaneously with the said moving of the blank in a curved path.
35. The method of claim 34 which includes the step of maintaining the inner wall of said blank in a condition unconfined longitudinally simultaneous with said moving.
36. In a method for forming straight tubular blanks into curved elbows, the steps comprising:
- providing a pair of blanks for movement in succession in a curved path,
  - positioning the leading end portion of an elongated mandrel and the trailing end portion of the first blank so that the mandrel is disposed within said first blank,
  - positioning the trailing end portion of said mandrel and the forward end portion of the second blank so that the mandrel is disposed within said second blank,
  - and moving said blanks and said mandrel in fixed relation around said curved path by pressing on the trailing end of the said second blank.
37. In a method of forming straight tubular blanks into elbows, the steps comprising:

12

- providing a blank for movement in a curved path,
  - positioning a mandrel having a generally banana-shaped compound curved outer surface conforming to the outer wall of the finished piece desired forwardly of the forward end portion of said blank,
  - positioning the said forward end portion of said blank over said mandrel,
  - moving said blank and said mandrel in fixed relation around said curved path by pressing on the trailing end of the blank,
  - and permitting said mandrel to rock during curved movement of the blank and mandrel so that said compound outer surface progressively supports against flattening the outer wall of said blank from the forward end of the blank rearwardly toward the midportion thereof.
38. In a method for forming straight tubular blanks into elbows, the steps comprising:
- positioning a blank for movement in a curved path,
  - and moving said blank around said curved path while simultaneously supporting the outer wall of the blank against flattening progressively from the forward end of the blank rearwardly to about the midportion thereof.
39. The method of claim 38 which includes the step of supporting the forward end of the inner wall of said blank against collapse simultaneously with said moving of the blank in a curved path.
40. In a method for forming straight tubular blanks into elbows, the steps comprising:
- providing a blank for movement in a curved path,
  - positioning the leading end portion of said blank over a first mandrel member,
  - positioning the trailing end portion of said blank over a second mandrel member,
  - and moving said blank and said mandrel members in fixed relation around said curved path by pressing on the trailing end of said blank while longitudinally confining the outer wall of the blank.
41. The method of claim 40 which includes the step of yieldingly resisting the movement of said blank and mandrel members.
